BAR OF SOAP OR THE LIKE

Willard Reeder Horne, Northvale, N.J., assignor to The Procter & Gamble Company, Cincinnati, Ohio, a corporation of Ohio

Filed Jan. 30, 1964, Ser. No. 78,423

Term of patent 14 years

(Cl. D73—1)

Fig. 1

Fig. 2

Fig. 3

Fig. 4

Fig. 5

FIG. 1 is an end elevational view of a bar of soap or the like, showing my new design.

FIG. 2 is a top plan view of the same.

FIG. 3 is a side elevational view of the same.

FIG. 4 is a cross-sectional view taken on the line 4—4 of FIG. 2.

FIG. 5 is a perspective view of the same.

The sides not shown are respectively the same as the opposite sides shown.

I claim:

The ornamental design for a bar of soap or the like, as shown and described.
